(57) **CLAIM**

The ornamental design for a trim for light fixture, as shown and described.

DESCRIPTION

FIG. 1 is an isometric view of a first embodiment of the trim for light fixture of the present invention;

FIG. 2 is a front elevation view thereof;

FIG. 3 is a right side elevation view thereof, the left side elevation view being a mirror image thereof;

FIG. 4 is a top plan view thereof;

FIG. 5 is a bottom plan view thereof;

FIG. 6 is a bottom view of a second embodiment incorporating the same trim as the first embodiment;

FIG. 7 is an isometric view of a third embodiment incorporating the same trim as the first embodiment; and,

FIG. 8 is an isometric view of a fourth embodiment incorporating the same trim as the first embodiment.

The broken line showing is for illustrative purposes only and forms no part of the claimed invention.
